UNITED STATES PATENT OFFICE

CARL HERMAN LEUFSTADIUS, OF LYSEKIL, SWEDEN

REVERSING DEVICE FOR INTERNAL-COMBUSTION ENGINES

Application filed April 24, 1926. Serial No. 104,358.

This invention relates to a device for reversing the direction of operation of internal combustion engines while in operation and more particularly to that type of such devices in which compressed air or gas is used as driving medium in effecting the reversing operation.

The object of this invention is to effect in a more reliable manner than heretofore possible a positive and quick reversing of both single cylinder and multi-cylinder internal combustion engines.

The methods as hitherto used to effect the reversing of internal combustion engines are, chiefly, of two kinds, namely (1) reversing by counter explosion and (2) reversing by means of compressed air.

Reversing by counter explosion has the following drawbacks: If a misfire occurs when reversing is to be effected this may cause the engine to stop. In four-cylinder engines the ignition should take place in two cylinders at a time in order to produce a sufficiently high torque to bring about the reversing operation and, furthermore, a smaller flywheel than that ordinarily used must be used resulting in a disadvantageous influence upon the coupling and the propeller in case of a boat engine.

In the known method of reversing by means of compressed air said air is supplied to all of the cylinders of the engine during the expansion stroke. Owing thereto a large amount of air is required, as almost the entire space of all of the cylinders will be filled with air, generally during several revolutions. Furthermore, the engine must be stopped to be then again started in the opposite direction of movement in which case a large period of time is spent in starting. As the air supplied to the cylinders expands an effective cooling of the combustion chamber will take place, and the means designed for enabling the starting will, consequently, be cooled so that misfire may occur. Such an arrangement can only be used in connection with multi-cylinder engines.

The present invention has for its object to provide a reversing device by which the above stated difficulties inherent to the counter ex-

plosion reversing method and the compressed air reversing method will be obviated. The new reversing method requires only one cylinder to effect the reversing. A further advantage, due thereto, is that the same type of reversing device may be used in single-cylinder engines as well as in multi-cylinder engines and, furthermore, the air consumption will be reduced to a minimum.

The invention is characterized, chiefly, by the provision of an additional valve gear, as a detent, centrifugal or other valve gear which, after the ordinary governor controlling the admission of fuel has been automatically disconnected prior to the reversing, will open a valve to admit air or gas under pressure from a receptacle into the cylinder during the upstroke of the piston at a proper number of revolutions and an appropriate angle of crank for effecting the reversing operation, the air thus supplied to the cylinder preventing the piston from moving towards the combustion chamber and, before the piston reaches its upper dead center, the air will cause the piston to again move downwardly thereby effecting a reversing of the direction of movement of the engine.

The invention is illustrated in the accompanying diagrammatic drawing which shows one embodiment thereof.

Figure 1 illustrates the normal position of the reversing mechanism with the engine operating clockwise.

Figure 2 shows the position of said mechanism when reversing is to take place from clockwise to counter clockwise operation.

Figure 3 shows the position of the reversing mechanism immediately after said reversing operation has been completed.

Figure 4 shows the same position with the reversing valve gearing in normal position.

Figure 5 shows the position of the mechanism when adjusted for reversing the engine from counter-clock-wise to clockwise operation.

Figure 6 shows the position of the mechanism immediately after said reversing operation has taken place.

Figure 7 is a side elevation of the en-

gine with the reversing mechanism applied thereto.

With reference to the drawing the numeral 1 indicates a receptacle containing compressed air or gas, as exhaust gases from an internal combustion engine or another suitable gas. The receptacle 1 is connected by a pipe 2 to the casing 3 of a valve 4. Said valve controls the connection between the pipe 2 and a pipe 5 leading to cylinder chamber 7 above the piston 8 of the engine to be reversed. The connection between the pipe 5 and the chamber 7 is controlled by a non-return valve 6 adapted to be opened automatically by the pressure of the gas within the pipe 5.

The valve 4 is controlled by a valve gearing, comprising a detent 9, operated by an eccentric on a shaft 10, which is operatively connected with the engine shaft, and a striking piece 11 carried by a lever 12 pivotally mounted on the journal 13. A spring 14 tends to maintain said lever in a position as shown in Fig. 1 in which the piece 11 keeps the detent out of operation. The lever 12 is articulated to a fork shaped friction element 15, arranged to cooperate with the shaft 10 as hereinbelow described. A spring 16 connects the lever 12 to a detent 17 of a valve gearing operated by an eccentric on a shaft 10^a driven from the engine and controlling a fuel valve 18 of the engine. A spring 19 connects the friction fork 15 to a hand lever 20.

The operation of the mechanism described is as follows:

The detent 9 is so arranged and driven that, when in operation, it will open the valve 4 during the up-stroke of the piston 8 at a certain reduced number of revolutions.

In the position shown in Figs. 1 and 7 the hand lever 20 is in its normal position both legs of the fork 15 are held out of engagement with the shaft 10. In this position the detent 17 is in its normal position, while the detent 9 is maintained out of operation by the lever 12. The engine is assumed to operate in clockwise direction as indicated by the arrow "a" to the right in the figure.

When it is desired to reverse the direction of operation of the engine, the hand lever 20 is turned to the right as shown in Fig. 2 of the drawing so that the lower leg of the fork 15 will come into frictional engagement with the shaft 10. This engagement will give the fork a downward movement, as is readily understood. The fork, in moving downwards, causes the lever 12 to turn on its pivot 13 so as to allow the detent 9 to assume its operative position. At the same time the spring 16 is stretched, swinging the detent 17 out of operative position, as shown. The fuel supply will, consequently, be interrupted, successively reducing the speed of the engine. At a suitably reduced speed, the de-

tent 9 is allowed to strike the valve 4 in the upstroke of the piston 8, allowing compressed air or gas from the receptacle 1 to enter the cylinder chamber 7 through the pipe 5 while opening the valve 6. This compressed air or gas will cause an increase of the pressure within the chamber 7 above the compression pressure corresponding to the respective position of the piston. In the continued upward motion of the piston the pressure within the cylinder chamber 7 will further increase due to the compression to a value above that of the pressure within the receptacle 1, causing the non-return valve 6 to close. The continued upward movement of the piston 8 will be prevented due to said increased pressure and before the piston reaches its upper dead center it will be caused to stop and move downwardly.

The reversal of the engine will, of course, also reverse the rotation of the shaft 10 with the result that said shaft, due to its frictional engagement with the lower leg of the fork 15 will cause said fork to move upwardly allowing the lever 12 to throw the detent 9 out of operative position and again restore the detent 17 to operative position as shown in Fig. 3.

After the reversing operation is completed, the hand lever 20 may be restored to its neutral or normal position in which it holds the fork out of engagement with the shaft 10. This position is shown in Fig. 4. The engine is now running counter-clockwise.

When it is desired to again reverse the engine, that is, from counter-clockwise to clockwise operation, the hand lever 20 is moved to the left as shown in Fig. 5. The upper leg of the friction fork 15 will now come into contact with the shaft 10, resulting in a downward movement of the fork 15 so as to throw the detent 9 into operation, while bringing the detent 17 out of operation. The reversing operation is now performed in the same way as above described. Fig. 6 illustrates the position after the engine has been reversed from counter-clockwise to clockwise operation. After the completion of this reversing operation the hand lever may be restored to its normal position as shown in Fig. 7.

What I claim is:

A device for reversing internal combustion engines while in operation, comprising in combination with a valve gearing for controlling the admission of fuel to the engine, means to supply a gaseous medium under pressure, a valve to control the admission of such medium to the cylinder of the engine, a valve gearing operated by the engine to open said valve during the upstroke of the piston of said cylinder at a number of revolutions so reduced as to cause said piston to stop and immediately reverse its movement before reaching its upper dead center,

- a shaft driven by the engine, manually controlled means to be operated by frictional engagement with said shaft and reversed when the engine is in reversed direction to
5 automatically bring the said last-mentioned valve gearing into operation at a certain direction of rotation of said shaft and out of operation at reversed rotation of said shaft, and a connection between said means and the
10 gearing of the fuel admission valve to maintain one of said valve gearings out of operation when the other is in operation, and vice versa.

In testimony whereof I have signed my
15 name.

CARL HERMAN LEUFSTADIUS.
